UNITED STATES PATENT OFFICE

ARCHIE T. MORRISON, OF SOUTH BRAINTREE, MASSACHUSETTS, ASSIGNOR TO S. H. COUCH COMPANY, INC., OF QUINCY, MASSACHUSETTS, A CORPORATION OF MASSACHUSETTS

DESIGN FOR A FRONT PLATE FOR FLUSH TELEPHONES

Application filed July 8, 1931. Serial No. 40,454. Term of patent 14 years.

To all whom it may concern:

Be it known that I, ARCHIE T. MORRISON, a citizen of the United States, and a resident of South Braintree, town of Braintree, in the county of Norfolk and Commonwealth of Massachusetts, have invented a new, original, and ornamental Design for a Front Plate for Flush Telephones, of which the following is a specification, reference being had to the accompanying drawings, forming a part thereof.

In the accompanying drawings
Figure 1 is a view in front elevation,
Fig. 2 is a view in side elevation, and
Fig. 3 is a view in section on the line 3—3
of Fig. 1.

I claim:

The ornamental design for a front plate for flush telephones, substantially as shown.

ARCHIE T. MORRISON.
